UNITED STATES PATENT OFFICE.

SAMUEL C. SIGMAN, OF GLADWIN, MICHIGAN.

DOOR-LOCK.

1,341,599.

Specification of Letters Patent. Patented May 25, 1920.

Application filed October 21, 1918. Serial No. 259,040.

To all whom it may concern:

Be it known that I, SAMUEL CHRISTOPHER SIGMAN, a citizen of the United States, residing at Gladwin, in the county of Gladwin 5 and State of Michigan have invented new and useful Improvements in Door-Locks, of which the following is a specification.

This invention has reference to improvements in door locks and resides in the construction, combination and operative arrangement of parts set forth in the following specification and falling within the scope of what is claimed.

The accompanying drawings illustrate a 15 simple and satisfactory embodiment of the invention, and in the said drawings:

Fig. 1 is a perspective view of a portion of a door having a lock thereon in accordance with this invention;

Fig. 2 is an inner face view of one of the escutcheon plates;

Fig. 3 is a sectional view approximately on the line 3—3 of Fig. 2;

Fig. 4 is an elevation of the lock, one of 25 the side or face plates being removed;

Fig. 5 is a sectional view approximately on the line 5—5 of Fig. 4;

Fig. 6 is a sectional view approximately on the line 6—6 of Fig. 4;

Fig. 7 is a sectional view approximately 30 on the line 7—7 of Fig. 4;

Fig. 8 is a view, similar to Fig. 4 with all of the parts removed except the tumbler and the auxiliary locking bolt;

Fig. 9 is a plan view of several of the 35 ward plates;

Fig. 10 is a perspective view of the locking bolt; and

Fig. 11 is a plan view of the latch bolt, 40 parts being broken away and parts being shown in section.

Fig. 12 is a view of the key employed.

Fig. 13 is a view of the key employed in fastened position.

45 In the drawings I have illustrated my improvement in the form of a mortise lock, but it is to be understood that the same may be in the nature of a rim lock if desired.

In connection with the lock I have shown 50 a door 12 provided with escutcheon plates 13 for the lock 14. These plates 13 are provided with the usual openings for the spindle 15 of the knobs 16 and with the usual keyhole openings 17. Upon the inner 55 face of each of the escutcheon plates 13, op-

posite the keyhole opening 17 is arranged a revoluble disk 18 having a single slot 19 of a length equaling that of the keyhole opening 17. It will be apparent that the slot 19 must be brought to align with the longer slot in the keyhole opening 17 before the key can be inserted, and that the bit of the key contacts with the walls provided by the slot 19 in the disk, so that the turning of the key will also cause the disk to turn, and the key can not be accidentally removed from the escutcheon plate. It is to be understood that the door 12 is provided with a suitable notch for the disk and for the bit of the key, the inner wall of the said notch terminating a suitable distance from the side of the lock 14, and by this arrangement the key may be at all times retained on the inner escutcheon plate 13, if desired.

The body of the lock 13 is of the usual construction, comprising a substantially rectangular flanged casing 20 having a removable side plate 21. The side plate, as well as the casing have alining keyhole openings, and these members, inward of the said openings are provided with revoluble disks 22 respectively, each of the said disks having a slot 23 designed to align with the keyhole opening, and when the key is inserted through either of the openings the turning thereof will cause both of the disks to revolve or turn, thus closing the keyhole openings in the lock casing and plate and preventing the accidental removal of the key from the lock, in addition to providing protecting means for the lock, to prevent the inner parts thereof being surreptitiously tampered with by skeleton keys or other instruments.

In the casing 20, adjacent the lower portion thereof is arranged an auxiliary locking bolt 24 disposed to slide between suitable ways and having its under face formed with spaced notches 25. To the lower flange of the casing is secured the ends of a substantially V-shaped spring 26, and to the inner end of the auxiliary bolt 24 is pivotally connected a link 27 that has its free end pivoted to a disk 28. The disk is provided with an operating handle 29, the link being eccentrically connected to the said disk, and by the turning of the handle the link will move the auxiliary bolt longitudinally permitting the central portion of the V-shaped spring to engage in either of the notches 25.

to turn the bolt in its locking or in its retracted position.

One of the disks 22 in the casing 20 has arranged thereover a plate or enlargement 5 30, suitably notched to receive the upper portion of the disk, and extending laterally from this plate or enlargement is a plurality of pins 31 that are arranged in staggered relation. The inner pin, or the pin nearest 10 the inner end of the casing serves as a pivot for a tumbler plate 32, the said plate being provided with elongated openings receiving the remaining pins 31, so that these pins serve as a guide for the tumbler and limit 15 the swinging movement thereof in two directions. The tumbler, at its upper and inner corner is provided with an outturned lug 33.

Arranged upon the face of the tumbler, 20 but out of contact with the lug 13, and supported upon the pins 31, is a plurality of ward plates 34. These plates 34 are interchangeable and are provided, upon their lower edges with arcuate notches 35, varying 25 in width and depth. The ward plates preferably have one of their faces provided with depressions 36 surrounding the notches 35 therein. Any desired number of ward plates may be employed, and the same being 30 interchangeable may receive the wards on the bits of different keys, only one key, of course, being employed to lock the lock, but at the same time the arrangement provides what may be termed a combination so 35 that another key having different sized wards may be employed.

By reference to the drawings it will be noted that the upper central pin 31 projects a suitable distance beyond the remaining 40 pins, or in other words is longer than the remaining pins, and this pin contacts with the upper edge of the slideable locking bolt 37. The lower edge of the bolt rests on the upper way for the auxiliary locking bolt 24. 45 The bolt, from the inner edge thereof, and upon its outer face is provided with a depressed portion 38, and the said depressed portion is notched or cut away in any desired shape from the lower edge thereof, as 50 indicated by the numeral 39. The notch or cut-away portion is designed to receive therein the first ward of the bit and the depressed portion permits of the turning of the key not provided with the proper wards 55 being turned around the bolt without influencing the same, even should the key have its remaining wards shaped to turn through the notched portions of the ward plates.

The locking bolt 37 has its upper edge 60 provided with two spaced notches 40 and 41 respectively, the lug 33 of the tumbler plate being received in the notch 40 when the bolt is in its retracted position and in notch 41 when the bolt is in its projected 65 position.

It is, of course, to be understood that the key 75, in operating the locking bolt first contacts with the lower edge of the tumbler, to swing the said tumbler, upon its pivotal connection with one of the pins 31 upwardly 70 of the casing, and thereafter will contact with the shoulder provided by the notched or cut-away portion 39 in the locking bolt to move the said bolt longitudinally of the casing. The notch in the lower edge of the 75 tumbler is such that the key, when retracting the bolt will not engage with the edge thereof, but the notch 39 in the bolt is such that the key will engage therewith, and thus draw the bolt inwardly to bring the notch 80 40 in a position to receive the lug 38 on the tumbler. The key sweep plainly illustrated in Fig. 4 of the drawings is indicated by the numeral 39.

The tumbler is influenced, in bolt engaging position through the medium of a two-arm spring 42, the said spring being centrally bent upon itself to provide a coil or eye 43 that is received on a stud 44 on the casing 20, one arm of the said spring 90 overlying the lug 33.

The latch bolt is indicated by the numeral 45 and has its shank provided with an opening therethrough, the end walls of which being beveled in opposite directions to the 95 center thereof. The opening is indicated by the numeral 46 and is designed to receive therein the second arm of the spring 43, the said spring influencing the latching bolt to an outward or operative position. The 100 shank of the latch bolt, upon the inner end thereof is formed with two spaced rearwardly extending curved arms 47 respectively, each of which having an elongated slot 48, and passing through these slots are 105 pins 49 secured to disks 50 that are connected to a hub 51, the said hub being disposed between the arms 47 of the latch bolt. The hub and the disks are provided with alining squared openings 52 which receive the squared spindle 15 for the knobs 16.

From the foregoing description, when taken in connection with the drawings, the advantages of the construction and the operation thereof will, it is thought, be apparent to those skilled in the art to which such inventions appertain, it being understood, however, that I am not to be restricted to the device as illustrated and described, but 115 am entitled to all such modifications as fall within the scope of what is claimed.

Having thus described the invention, what is claimed as new is:—

1. In a door lock, slotted revoluble disks 125 opposite the key openings therein, a plate in the casing having a notch receiving the disk, staggered pins projecting from said plate one of which being of a greater length than the others, a spring influenced tum- 130

bler pivotally arranged on one of the pins and limited in its movement by the remaining pins, notched guard plates interchangeably supported by the pins, a slideable bolt 5 contacting with the longer pin and engaged by the tumbler, and a ledge in the casing providing a support for the lower edge of the bolt.

2. In a door lock, a spring influenced 10 pivoted tumbler arranged over the key openings therein, a slideable locking bolt normally engaged by said tumbler, interchangeable notched ward plates between the tumbler and bolt, and said guard plates having 15 depressions surrounding the notches thereof.

3. In a door lock, a tumbler comprising 20 a pivoted plate having an offset lug, spring means for moving the tumbler in one direction, means for limiting the swinging of the tumbler in both directions, a slideable locking bolt having spaced notches engaged by the lug on the tumbler, and interchangeable notched ward plates between the tumbler 25 and bolt.

4. In a door lock, rotatable notched disks 30 surrounding the key openings therein, a spring influenced pivoted tumbler, means for limiting the swinging movement thereof, a slideable locking bolt having spaced

notches engaged by the tongue, interchangeable ward plates between the tumbler and locking bolt, an auxiliary bolt below the locking bolt having spaced notches, a V-shaped spring designed to engage in one 35 of said notches, a link on said auxiliary bolt, a disk, an operating handle for the disk, and said link being eccentrically connected with the disk.

5. In a door lock, rotatable disks 40 surrounding the key opening therein, and having notches designed to align with the said openings when the said disks are in one position, a notched pivoted tumbler, spring means for moving the tumbler in one direction, 45 a slideable bolt having spaced notches engaged by said tumbler, notched interchangeable upright plates between the tumbler and bolt, an auxiliary locking bolt, a latch bolt influenced by the spring engaging 50 with the tumbler, said latch bolt having its inner end provided with spaced arms having elongated slots, a hub carrying a spindle between the arms, disks on the opposite sides of the hub, and pins in said disks 55 engaging in the slots in the said arms.

In testimony whereof I affix my signature.

CRISS SIGMAN.
